COMBINED FUSE AND SWITCH STRUCTURE

Homer E. Malone, Milwaukee, Wis., assignor to
Perfex Corporation, Milwaukee, Wis., a corporation of Wisconsin

Application January 8, 1941, Serial No. 373,564

13 Claims. (CL 200—114)

This invention relates in general to combined fuse and switch structures and the principal object of the invention is to provide a new and improved fuse and switch mechanism combined in a housing as a unitary structure.

A further object is to provide a combined fuse and switch mechanism and housing therefor in which access to the fuse is prevented until the switch has been moved to the "off" position.

Another object is to provide a combination fuse and switch structure in which the switch is provided with three different positions; one in which the switch is "on"; a second in which the switch is "off"; and a third in which the switch is "off" and the fuse is rendered accessible.

An additional object is to provide an improved fuse and switch housing or casing in which a part of the housing is utilized to enclose the fuse to render it inaccessible and also serves as the means for actuating the switch mechanism.

A further object of the invention is to provide a compact unitary structure of the fuse and switch elements having a minimum number of parts together with a housing comprising a base portion for enclosing the switch elements and a cover portion enclosing the fuse.

It is customary in many cases to provide a metal switch box having a hinged cover thereon, which switch box encloses a screw type fuse supported in a receptacle. In addition, a line switch is included in the box having a handle therethrough whereby the line switch conductors are opened and closed by manipulation of the handle. Many times when a fuse is blown and is removed and a new one inserted, the person performing the operation comes into contact with the exposed terminals of the line switch, and is negligent about disconnecting the line switch when such a fuse replacement is made. The operation is thereby attended with some danger. In certain other cases, if a fuse is blown due to a short circuit in the line and the line switch is not thrown to open position, the insertion of a new fuse causes its blowing while the operator still has it in his hand. It is accordingly an object of this invention to obviate the foregoing dangers to an operator when renewing a fuse, by providing an arrangement in which access to the fuse plug is prevented while the line switch is in a closed position. In accordance with the above, a further object is to provide a combination switch actuating member and fuse cover as a single unitary combination instead of separate elements as pointed out.

The foregoing and other objects and features

of the improved fuse and switch mechanism reside in certain novel features of construction, arrangement and combination of the various elements and parts which will be hereinafter more fully described, particularly pointed out in the appended claims, and illustrated fully in the accompanying drawing, in which:

Fig. 1 is a full perspective view of the combined fuse and switch housing structure embodying the invention;

Fig. 2 is a cross sectional side view of the fuse and switch structure and housing therefor;

Fig. 3 is a bottom view of the structure showing the switch elements in the "off" position;

Fig. 4 is a similar view with the switch elements shown in the "on" position; while

Fig. 5 is a perspective view of all of the elements embodying the fuse and switch structure shown in extended relationship.

Referring now particularly to the drawing, the various switch elements are arranged within a hollow casing or housing 5 formed into the shape illustrated, and constituted preferably of some molded plastic insulation material. The hollow open end of the housing 5 may be enclosed by an insulating plate 6 and the whole structure supported in any desirable position by means of screws or bolts passing through holes 7 on opposite ends of the housing 5. The housing 5 is formed with a flat supporting base portion 8 having a cylindrical barrier portion 9 formed integral therewith and projecting outwardly from the surface thereof. Positioned within the cylindrical portion 9 and having its bottom surface resting against the supporting base 8 is a metal fuse receptacle or shell 10 adapted to receive in screw threaded relationship therewith a fuse plug 11 of well known construction. The center terminal of the fuse plug 11 is adapted to establish electrical contact when screwed into receptacle 10, with the head of a screw 12 which projects through an opening in the supporting base 8 into the hollow portion of the housing 5.

A metal fuse enclosing and switch operating knob or member 13 of the same general cylindrical shape as the barrier 9 fits snugly over the barrier 9 and serves to enclose the fuse 11. The knob 13 is arranged to project forwardly from the base portion 8 of the housing 5. The barrier portion 9 of the housing 5 electrically insulates the inside surface of the operating knob 13 from the fuse element 11 and fuse shell 10. In order to establish electrical contact with the fuse receptacle 10 a contact plate 14 is arranged to rest in contact with the bottom of the fuse re-

ceptacle 10 and is provided with a projecting bracket portion 15 extending through a slotted opening 16 in the fuse receptacle 10 (Fig. 5) and a coinciding opening 17 in the supporting base 8 of the fuse housing 5. In order to insulate the head of screw 12 which is in contact with the center contact of the fuse plug 11, from the contact plate 14, an insulating washer 18 is interposed therebetween in the bottom of the fuse receptacle 10. The foregoing elements, except for the fuse plug 11, are all held in assembled relationship within the cylindrical barrier portion 9 of the housing 5 by means of the screw 12.

Arranged on the opposite side of the supporting base 8 within the hollow portion of housing 5 is a switch centering disc or member 19 preferably made of some insulation or ceramic material, having shoulder portions 20 which are adapted to interfit with the opening 16 in the fuse receptacle 10 and opening 17 in the supporting base 8. The switch centering member 19 is also provided with a projecting and recessed portion 21 adapted to fit over a portion of the contact bracket 15 to securely hold it in its assembled position. The opposite side of the switch centering member 19 is formed with a series of raised and recessed portions 22 which serve as the switch positioning or centering means. The switch centering member 19 is confined in its position by means of a protruding portion 23 formed integral with and projecting rearwardly as a continuing portion of the barrier 9 on the front of the supporting base 8. Passing through the supporting base 8 and arranged on opposite sides of the outer surface of barrier 9 and the extending portion 23 are a pair of slots 24 and 25 which are slightly wider than the thickness of the operating knob 13. The end of each slot 24 and 25 is arranged with slightly wider openings 26 and 27 respectively, which enlarged openings are adapted to receive forked projections 28 and 29 (see Fig. 5) which are formed integral with the inner end of the operating knob 13. The forked members 28 and 29 are slightly offset from the plane of the sides of the operating knob 13 so that they may be inserted freely in the openings 26 and 27, and when the operating knob 13 is rotated the offset portion of each fork engages the bottom side of the supporting base 8 and holds the operating knob 13 locked onto the base 8. It is seen that only when the operating knob 13 is rotated to a position where the forked elements 28 and 29 register with the openings 26 and 27 can the operating knob 13 be removed from the base 5 to render the fuse 11 accessible.

One of the switch elements of the device comprises a flat contact plate 30 having a tongue portion 31 positioned within a recessed central portion of the switch centering member 19. The contact plate 30 has a screw threaded extension centrally located which is adapted to receive the threaded shank portion of the screw 12. When the head of screw 12 is tightened into the contact plate 30 all of the elements 10, 14, 18, 19 and 30 are securely clamped together to the supporting base 8. The second switch element 32 is formed out of a contact bracket 33 which is positioned as shown in Fig. 3 at the opposite side of the housing 5 from the contact bracket 15. The switch elements 31 and 32 are so arranged upon the switch centering member 19 that they lie in the same plane and diametrically opposite each other. A contact bridging member 34 for bridging the switch elements 31 and

32 and formed of some brass material into a star shape as shown is arranged for rotation upon the reduced portion of screw 12. The arms of the bridging switch member 34 are arranged to receive an insulating switch operating member 35 formed generally into the same shape as the switch member 34 but having a pair of oppositely disposed arms extending beyond the ends of the switch member 34.

The ends of the insulating operating member 35 are adapted to receive the forked ends of the elements 28 and 29 of the operating knob 13 for the purpose of actuating the same, and to thereby bridge and unbridge the contact elements 31 and 32 with the switch member 34. The switch member 34 when rotated about screw 12 is adapted to snap from one of the positions 22 of member 19 to the other. In order to provide for this snap action a tension coil spring 37 is arranged to encircle the extended portion of screw 12 and exert a constant pressure on one side of the switch member 34. A bearing washer 36 is preferably arranged between the end of spring 37 and the operating member 35. In order to protect the internal switching mechanism and to also enclose the same, a flat insulating plate 38 is provided which is arranged with a notched portion at opposite ends to permit contact brackets 15 and 33 to project therethrough. The plate 38 at the same time engages a projection 33' formed on contact bracket 33 for the purpose of holding the same in its position within the casing 5. Both contact brackets 15 and 33 are provided with bent over portions which are adapted to be seated into offset portions of the housing 5 so as to properly position the brackets and prevent their displacement. A metal cap 39 straddles the opening in insulating plate 38 and serves to restrain one end of the coil spring 37. A snap lock washer 40 engaging a notch in the end of screw 12 completes the assembly and holds the metal cap in position.

With the foregoing assembly it is seen that a simple arrangement of elements is provided which may be readily assembled or disassembled by merely removing the snap washer 40 whereupon each of the elements inside the housing 5 can be removed in the sequential order as illustrated in Fig. 5. By merely removing the screw 12 from threaded engagement with the contact plate 30, the remaining elements in the barrier member 9 may be readily disassembled.

In order to provide a connection for the external electric wires to the contact plates 15 and 33, terminal screws 41 and 42 are threaded into the offset portions respectively of the foregoing plates. To facilitate the rotary manipulation of the operating knob 13 its forward edge portion is provided with a knurled surface 43. The end of the knob 13 also has an arrow stamped thereon which in cooperating with suitable indicia marked upon the supporting base 8 indicates the relative position of the bridging member 34 and also the position in which the knob 13 may be removed to render the fuse 11 accessible.

The electrical connections of the switch device extend over the following path: from the conductor (not shown) attached to terminal screw 41, contact bracket 15, contact plate 14, through the fuse shell 10 which is in contact with the contact plate 14, the outer brass shell of the fuse 11, through the fuse element (not shown), the center contact post of fuse 11, the head of screw 12, in contact therewith, through contact plate 30 which is in screw threaded engagement

with the screw 12, switch contact point 31 of plate 30, through oppositely disposed arms of the contact bridging member 34 to switch contact plate 32, contact bracket 33, and out through the conductor of the "hot" side of the line attached to terminal screw 42. In this circuit path it is seen that the switch positioning disc 19 is interposed between the contact brackets 15 and 33 while the insulating washer 18 electrically insulates the head of screw 12 from the fuse shell 10 and contact plate 14. The "hot" side of the line circuit is broken by the switch elements 31, 32 and 34 at a point ahead of the fuse elements 11 so that when the switch is open the fuse is dead.

Under ordinary conditions the switch device is mounted in a horizontal position so that the operating knob 13 projects horizontally from its mounting plate 6 and in a position where it is readily visible and accessible for mutual manipulation. When serving in the capacity of a combination line switch and fuse holder the "hot" line feed wire is connected directly to the terminal screws 42 and the "load" wire is connected to screw 41. When it is desired to connect the line circuit to some load for example, the operating knob 13 is grasped and rotated in a clockwise direction one step from the position illustrated in Fig. 1 to a position where the indicating arrow 44 on the top of operating knob 13 points to the designation "on" stamped on the supporting base 8. The manual rotation of operating knob 13 carries along with it the forked extensions 28 and 29, which being in detachable engagement with the ends of switch operating arm 35 rotate the arm and with it the contact bridging member 34. The position of the switch elements after the knob 13 is rotated one step is indicated in Fig. 4. In this position of Fig. 4 the contact switch plates 31 and 32 are electrically bridged by the member 34 thereby closing the circuit through the switch device in series with the fuse element 11. In this position of the operating knob 13 it is impossible to remove the knob 13 from the supporting base 8 to uncover the fuse 11, since the offset portions of the forked extensions 28 and 29 are now resting in a position in slots 24 and 25 where they are locked against the underside of supporting plate 8. It is therefore seen that it is impossible to gain access to the fuse element 11 while the switch device is in its circuit closed position.

In the event that the fuse 11 is blown, due to some circuit disturbance, or for some other reason it is necessary to remove the fuse, the operating knob 13 is rotated clockwise one step from the switch "on" position to a position where the indicator 44 registers with the "fuse" designation on the base 8. In this position the contact bridging member 34 is rotated to the position indicated in Fig. 3 in which position the forked extensions 28 and 29 register with the enlarged slotted portions 26 and 27 which are large enough to readily permit the forks to pass through the slots and out of engagement with the switch operating arm 35, whereupon the operating knob 13 is readily disassociated from the fuse 11 to uncover the same for replacement or other purposes. In this position of the contact bridging member 34 no circuit is established across the switch contact plates 31 and 32 so that the fuse and other elements of the switch are not electrically alive and the danger of accidentally receiving a shock by coming in contact with them is obviated.

In case it is desired that the switch device be rotated from its circuit closing position to its circuit opening position without removing the operating knob 13 or uncovering the fuse 11 the operating knob 13 may be rotated counter-clockwise from the "on" position to a position where the indicator 44 registers with the "off" indication on the supporting plate 8. In this position the forked extensions 28 and 29 rotate the switch operating arm 35 in a counterclockwise direction to where the bridging arm 34 is out of contact with the contact plates 31 and 32. This position is similar to that illustrated in Fig. 3 but with the switch operating arm 35 positioned 90 degrees counterclockwise from that illustrated. In this switch "off" position the operating knob 13 is not removable from the supporting base 8 since the offset forked extensions 28 and 29 are now resting on the underside of supporting base 8 where they prevent the removal of the operating knob 13.

From the foregoing it is seen that the switch device is adapted to be operated to three different positions, one in which the switch device is in circuit "on" position in which the fuse is inaccessible, a second position in which the device is in switch "off" position and in which the fuse is also inaccessible, and a third position in which the switch is in "off" position and at the same time arranged so that the fuse is readily accessible without danger of coming into contact with any "live" portions of the switching mechanism.

It is desirable that the contact bridging member 34 establish electrical contact or disconnect itself from the switch contact plates 31 and 32 with some degree of snap action in order that a quick circuit break or make is provided to minimize arcing conditions. It is also desirable that the rotation of the operating knob 13 to each of the three positions described be such that it is centered or snapped correctly in each of the positions and not half way between them. The coil spring 37 serves to provide this snap action by urging the switch operating arm 35 and the associated contact bridging member 34 in slidable relation with the bottom surface of the switch positioning disc 19. Since this disc 19 is provided with a series of diametrically positioned switch center projections 22 separated by raised portions, the bridging member 34 is accurately centered in the position to which it is rotated at each operation. The resiliency of the spring 37 and the sloping sides of the projections 22 combine to perform the stated function.

The switch device utilizes standard fuses 11 and fuse shells 10 and other elements and is arranged so that all of the various parts are in compact relationship and readily assembled. The switch operating mechanism is likewise readily accessible for observation and constructed ruggedly so as to function indefinitely and in a reliable manner.

The invention while illustrated in its preferred form as a switch device is capable of expression in various modifications readily comprehensible by those skilled in the art, and it is therefore desired that the invention be not limited to the precise structure illustrated and described but only within the scope of the appended claims.

What is claimed is:

1. In a switch device, a housing including a supporting base, a fuse receptacle arranged at the front of said supporting base and a switching mechanism at the rear thereof, an operating knob enclosing said fuse receptacle to render it

inaccessible and having a portion extending through said base into engagement with said switching mechanism, an insulating barrier projecting from said base and arranged between said fuse receptacle and said operating knob, said insulating barrier having a portion extending through said supporting base into said housing for supporting the switching mechanism therein, and cooperating means on the supporting base and the portion of the operating knob projecting through said supporting base for detachably securing said operating knob to said housing in operable relation with said switching mechanism.

2. In a switch device, a switch housing including a supporting base, a fuse receptacle arranged at the front of the supporting base and projecting therefrom, a switching mechanism arranged at the rear of said supporting base and within said housing, an insulating barrier projecting from said supporting base around said fuse receptacle, an operating knob on said supporting base enclosing said fuse receptacle and surrounding said insulating barrier, said operating knob having means passing through said supporting base for engaging said switching mechanism to operate the same, and a unitary means for holding said fuse receptacle and said switching mechanism to said supporting base.

3. In a switch device, a housing including a supporting base, a fuse receptacle arranged at the front of said supporting base, switching mechanism arranged at the rear of said supporting base and within said housing, said switching mechanism including contact means and a circuit bridging member for said contact means, terminal connecting means for said contact means arranged within said housing, an insulating member for retaining said bridging member in contact opening and closing position when actuated thereto, and single means extending through said supporting base for securing said fuse receptacle, said contact means, said bridging means, said terminal connecting means and said insulating member in assembled relationship.

4. In a switch mechanism, for an electric circuit, a housing including a supporting base, a fuse receptacle arranged upon the front of said supporting base and outside said housing, switching mechanism arranged upon the rear of said supporting base inside said housing, a rotatable operating knob enclosing said fuse receptacle and having projecting means thereon extending through said supporting base into engagement with said switching mechanism for operating the same to circuit opening and circuit closing positions, said switching mechanism comprising, stationary switch contact plates and a contact bridging member actuated by the operating knob, means on said supporting base for insuring the centering of said bridging member and for providing snap action as it is moved from one position to the other, means for preventing the removal of the operating knob from the fuse receptacle when the operating knob is rotated to circuit opening or circuit closing positions, and means on said supporting base to permit the removal of the operating knob from the base to uncover the fuse receptacle when the operating knob is rotated to a third position.

5. In a switch mechanism for an electric circuit, a housing including a supporting base, a fuse receptacle arranged upon the front of said supporting base, switching mechanism arranged upon the rear of said supporting base, a rotat-

able operating knob enclosing said fuse receptacle to render it inaccessible and having projecting means thereon passing through said supporting base into engagement with said switching mechanism for operating the same to circuit closing and circuit opening positions, said switching mechanism comprising stationary switch contact plates and a bridging member engaged by the projecting means of the operating knob, means on said supporting base to provide snap action to the movement of said bridging member and to center the bridging member accurately in the position to which it has been operated, cooperating means on the operating knob and the supporting base to prevent removal of the operating knob from the supporting base while the switching mechanism is in circuit closing position, and means on said supporting base to permit removal of the operating knob from the supporting base and render said fuse receptacle accessible when the switching mechanism is in circuit opening position.

6. In a switch mechanism for an electric circuit, a supporting base, a fuse receptacle and a fuse element therein arranged on one side of said supporting base, switching mechanism arranged on the other side of said supporting base, said switching mechanism comprising a pair of switch contact plates and a bridging member, means for operating said bridging member into circuit closing and circuit opening relationship with said pair of switch contact plates, one of said switch contact plates being formed integral with a wire terminal member arranged on the rear of said supporting base, means for holding the other of said switch contact plates to the rear of said supporting base, said holding means comprising a screw member passing through said supporting base and in electrical contact with said other switch contact plate and with said fuse element, a disc member arranged in electrical contact with said fuse receptacle and having an extension formed thereon passing through said supporting base to the rear side thereof constituting a wire terminal member, and insulating means interposed between said disc member and said screw member, and between said pair of switch contact plates.

7. In a fused switch, a supporting base, a fuse receptacle supported on said base and having a fuse opening accessible from the front of the base to permit fuse replacement, a switching mechanism mounted on the base and located at the rear thereof so as to be inaccessible, a movable cover for covering the fuse, said cover being associated with means extending from the front of the base through the base to the rear thereof for actuating said switching mechanism upon movement of said cover.

8. In a fused switch, a supporting base, a fuse receptacle supported on said base and having a fuse opening accessible from the front of the base to permit fuse replacement, a switching mechanism mounted on the base and located at the rear thereof so as to be inaccessible, a movable cover for covering the fuse, and lug means attached to said cover and located at the rear of said base, said lug means being constructed and arranged to actuate said switching mechanism and to maintain said cover in place.

9. In a fused switch, a supporting base, a fuse receptacle supported on said base and having a fuse opening accessible from the front of the base to permit fuse replacement, a switching mechanism mounted on the base and located at

the rear thereof so as to be inaccessible, a removable cup-shaped cover for covering said fuse, and means for preventing removal of the cover without moving said switch to open position, said means including lug means attached to the cover and extending through the base for maintaining said cover in place and actuating said switching mechanism.

10. In a fused switch, a supporting base, a fuse receptacle supported on said base and having a fuse opening accessible from the front of the base to permit fuse replacement, a switching mechanism mounted on the base and located at the rear thereof so as to be inaccessible, a rotatable cover for covering the fuse, said cover being associated with means extending from the front of the base through the base to the rear thereof for actuating said switching mechanism upon rotation of said cover.

11. In a fused switch, a supporting base, a fuse receptacle supported on said base and having a fuse opening accessible from the front of the base to permit fuse replacement, a switching mechanism mounted on the base and located at the rear thereof so as to be inaccessible, a rotatable cover for covering the fuse and having lug means engaging the base at its rear for maintaining the cover in place, said lug means being constructed and arranged to transmit rotary

movement of the cover to said switching mechanism.

12. In a fused switch, a supporting base, a fuse receptacle supported on said base and having a fuse opening accessible from the front of the base to permit fuse replacement, a switching mechanism mounted on the base and located at the rear thereof so as to be inaccessible, a rotatable cover for covering said fuse and having means extending from the front of the base through the base to the rear thereof for actuating said switching mechanism, means associated with said extending means for engaging the rear of the base to maintain the cover in place, the base being formed with a slot cooperating with the last mentioned means to permit withdrawal of the cover when it is turned to a position causing the switching mechanism to be in open position.

13. In a fused switch, a base, a fuse receptacle mounted on said base and having a fuse opening accessible from the front of the base, said receptacle including a fuse contact having a rearwardly extending stud, a rotating switch arm pivoted to said stud and adapted for movement between circuit making and circuit breaking positions, a rotatable cover for said fuse receptacle, and means for transmitting rotary movement of said cover to said switch arm.

HOMER E. MALONE.
